Sellers Patent

which is referred to in the Sellers Patent and making part of the same, containing a description in the words of the said Amos. Sellers himself of his improvement in Fulling Mills and Power Looms.

To all to whom these presents may come, Be it known that I Amos Sellers of Salem in the County of Washington and State of New York, have invented a new and useful improvement in the construction of Fulling Mills and Power Looms, and that the following is a full and exact description of the nature of said improvement, its construction and operation as invented and applied by me.

It is usual in Fulling Mills to connect each hammer to the crank by means of an iron rod, or a stick of timber called a pinion, at the point where it is in the hammer and the crank, which some willers call the "Engine of oblique action". This is done by using a short pinion, and connecting it with the hammer by a compound lever, one end of this compound lever is fastened to the hammer, and the other end is fastened by a middle pin to the frame of the mill. Near the centre of the lever is a rolling joint, and at the joint, or between it and the free end of the lever I attach the pinion reaching from the crank. The joint is similar to those in the arms of a carriage-slope, and is furnished with a middle pin. The advantages of this improvement are a gain of power, and a more gradual and equable motion of the hammers, better concurring to the fulling of cloth, also a diminution of expense, in crank and pinion and repairs. In that Power Loom I apply my improvement for the purpose of giving the cloth a finer texture, by giving two blows instead of one in breaking it up. This I do by a compound jointed lever (similar to that used in the fulling mill) with one end attached to the lathe, and the other end to a pin on one of the posts of the loom. This lever is moved by a crank or cam wheel. The end of the lever attached to the post must be furnished with a dumb bell and nut, and a pin in the post

allowing the loom to be handled or depressed at pleasure as to cause two blocks upon every thread of setting. In the fulling mill which I have put in operation upon this Plan in the Town of Woburn the length of the beam is six feet. the joint exactly in the middle. the fuller unites with the lever seventeen inches from the joint, thus giving the hammer a proper motion upon a crank of ten inches sweep.

What I claim as new and as my own invention and is the application of a compound jointed lever or the engine of oblique action to a fulling mill and a loom I consider the construction and application as above set forth wholly my own and I claim the exclusive right of using the same together with the sole advantage derivable therefrom.
